UNITED STATES PATENT OFFICE.

ALBERT W. MORSE, OF LONG ISLAND CITY, NEW YORK.

LIQUID-FUEL BURNER.

Application filed May 23, 1923. Serial No. 640,873.

To all whom it may concern:

Be it known that I, ALBERT W. MORSE, a citizen of the United States, and a resident of Long Island City, in the county of 5 Queens and State of New York, have invented certain new and useful Improvements in Liquid-Fuel Burners, of which the following is a specification.

This invention relates to improvements 10 in liquid fuel burners and more particularly to burners of the externally mixing, low pressure, type, viz., burners in which the fuel and the air do not mix until after they are ejected from the burner and refers more specifically to burners which use 15 socalled "nebulizers" for atomizing the fuel oil into a very fine mist prior to mixing the same with the air, and in which nebulizers the atomizing effect is obtained by 20 direction of admission of the fuel oil into passages leading into a small swirling chamber.

It is an object of this invention to provide a burner of this type which operates 25 satisfactorily in conjunction with an intensely hot air supply. Another object is to provide within the burner and around the liquid fuel conduit a heat insulating chamber for the purpose of preventing excessive carbonization of the fuel oil. Additional objects, advantages and features 30 of the invention will appear from the construction, arrangement and combination of parts hereinafter described and shown in 35 the drawings, wherein—

Fig. 1 is a vertical longitudinal sectional view of the burner;

Fig. 2 is a transverse cross sectional view, taken along the plane of line 2—2, in Fig. 1; 40 Fig. 3 is an enlarged fragmentary section of the discharge end of the burner;

Fig. 4 is a cross sectional view along the plane of line 4—4 in Fig. 3; and

Figs. 5 and 6 show modifications of the 45 manner of effecting a tight joint at the nebulizer end of the heat insulating chamber.

Like characters of reference denote similar parts throughout the several views and 50 the following specification:

10 is a cylindrical casing of substantially L-shape, having a shorter branch 11 threaded 55 interiorly to receive a hot air supply pipe 12. The terminal of a longer branch 13 of casing 10 is threaded exteriorly at 14.

Casing 10 is threaded interiorly, adja-

cent to branch 11, to receive a plug 15, provided with a flange 16 to make a tight joint against the casing, and a hexagonal part 17 to facilitate screwing the plug 15 60 into the casing.

Plug 15 is bored out to receive an oil spindle 18. This oil spindle is of hollow construction, being provided with a central duct 19, and extends through the casing 10 65 in central alignment, with the branch 13. 20 is an enlarged upper end of spindle 18, threaded interiorly to receive a nebulizer plug 21.

Nebulizer plug 21 is provided in its center with a hollow core 22, cylindrical in shape, called the swirl chamber. 23 is a plug screwed into the lower part of plug 21 for the purpose of machining chamber 22. At the top of the chamber 22 and in 70 its center is a small circular outlet opening 24. 25 and 26 are small drilled passages 75 extending into the plug 21 at the sides of chamber 22. 27 and 28 are ducts or inlet orifices joining the innermost ends of 80 passages 25 and 26 with the upper part of chamber 22. These ducts are positioned so as to impinge the circumference of chamber 22 tangentially, as is shown in Fig. 4, and they are further slightly inclined towards 85 the outlet end. 29 is a polygonal projection around the outside of the plug 21, to facilitate screwing the same into the spindle. The top of the nebulizer 21 is chamfered at 30, so as to make the final outlet 90 passage 24 as short as possible.

15^a is a tube surrounding the oil spindle 18, and is threaded at both ends, the one end being screwed into a correspondingly threaded socket 15^b in plug 15, and the 95 other end having a deflector cap 31 screwed onto it, forming a closed chamber 15^c around the oil spindle 18.

Deflector cap 31, as shown in Fig. 1, 3 and 5, is provided with a circular central opening 32 which is smaller than the outside diameter of the nebulizer 21. Below 100 32 is a recess 33 within cap 31, of such diameter as to fit snugly, but slidingly, over the corners of the polygonal portion 29 of 105 plug 21. 34 is an oil deflecting surface extending from outlet 32 to the top of the cap, and 35 is an air deflecting surface surrounding the surface 34 on the top of cap 31, the included angle at which these 110 deflecting surfaces meet, being an acute one, that is, 90 degrees or less.

In Figs. 1 and 3, the top of the nebulizer 21 forms a tight joint with the bottom of the recess 33 in cap 31. In Fig. 5, a modification, a thickened portion 18^a of the oil spindle 18 makes a tight joint with the end of recess 33; and in a still further modified form of joint, shown in Fig. 6, the oil spindle 18 projects through the cap 31 from which the recess 33 has been eliminated, and a tight joint is maintained by the nebulizer 21 seating against the outside of the cap 31.

36 is a cap adapted to screw onto the threaded end 14 of branch 13 of casing 10, which cap is provided with a central opening 37 of a diameter larger than the circle in which surfaces 34 and 35 of cap 31 meet. 38 is an inner deflecting face of cap 36. 39 are lugs on the outside of the cap 36 to facilitate screwing the same onto the threaded part 14.

40 is a reduced portion of oil spindle 18, projecting outside of the casing 10 and is threaded exteriorly to receive a needle valve 41 of standard construction, controlling the flow of oil to the burner from a pipe 42.

The operation of the device is, as follows:

Oil, under pressure, passes through conduit 19 into the nebulizer 21, through passages 25 and 26 and from there through inlet orifices 27 and 28 into the swirl chamber 22. Owing to the direction of the inlet orifices, tangentially with respect to the wall of chamber 22, the oil is being given a swirling motion and is finally expelled in form of a very fine mist from outlet 24 where it assumes the shape of an inverted cone, guided by chamfer 30 on the outside of the plug and the oil deflecting surface 34.

Hot air, under pressure, enters the air chamber 10 via the inlet pipe 12 and is deflected under its full pressure into the spray or mist of oil. The resulting mixture leaves the main outlet 37 at high velocity.

In practice, it has been found that owing to the excessive heat around the oil spindle 18, in constructions as heretofore employed, the oil will carbonize very quickly and cause the outlet of the burner nozzle to be clogged up, eventually resulting in a shut-down of the burner. With the use of the heat insulating chamber 15^c, however, it is obvious that there is present an amount of stagnant air surrounding the oil spindle which is an excellent insulating medium, being a very poor conductor of heat. Small holes 15^d may be provided for at the lower end of the insulating chamber, through plug 15, if so desired, to allow for carrying off any excess of heat, but these are optional and may be dispensed with without affecting the insulating qualities of the chamber 15^c around the oil spindle.

While I have shown in the drawings the insulating chamber 15^c made of tubing and

threaded into a plug screwed into the casing, other means of providing this chamber may be used equally as well, so, for instance, a tubular extension may be cast integrally with the casing to form such a chamber, and the plug 15 screwed into the bottom of this chamber, or be dispensed with altogether.

It is further understood that while I have above described my invention as applied to one kind of burner, its use and application may be varied and serve other forms of burners as well.

Various other changes in the form, proportion and minor details of construction may be resorted to without departing from the principle or sacrificing any of the advantages of the invention, as defined in the appended claims.

What I claim as new, is:

1. In a liquid fuel burner, a hot air pipe, a fuel conduit projecting through the said hot air pipe, a nebulizer at the outlet end of the said fuel conduit, and an insulating chamber surrounding the said fuel conduit within the said hot air pipe, and a cap having a recess for the said nebulizer and forming a tight closure to the said insulating chamber.

2. In a liquid fuel burner, a hot air pipe, a fuel conduit projecting through the said hot air pipe, a nebulizer at the outlet end of the said fuel conduit, an insulating chamber surrounding the said fuel conduit within the said hot air pipe, and a cap contacting with the said nebulizer and forming a tight closure to the said insulating chamber.

3. In a liquid fuel burner, a hot air pipe, a fuel conduit projecting through the said hot air pipe, a nebulizer at the outlet end of the said fuel conduit, an insulating chamber surrounding the said fuel conduit within the said hot air pipe, a cap contacting with the said nebulizer and forming a tight closure to the said insulating chamber, and ports connecting the said insulating chamber directly with the atmosphere.

4. In a liquid fuel burner, a hot air pipe, a fuel conduit projecting through the said hot air pipe, a nebulizer at the outlet end of the said fuel conduit, and an annular insulating chamber surrounding the said fuel conduit within the said hot air pipe, the said insulating chamber being tightly closed at the end nearest the outlet end of the fuel conduit and having ports communicating directly with the atmosphere at its other end.

In testimony whereof I have hereunto set my hand and seal in presence of two subscribing witnesses.

ALBERT W. MORSE. [L.S.]
